P. G. DARLING ET AL

SAFETY VALVE

Filed Aug. 11, 1921

FIG. 3.

Inventors:
Philip G. Darling.
Carl H. Graesser.
By Robert Robert L. Lounsbury
his attorney.

UNITED STATES PATENT OFFICE.

PHILIP G. DARLING AND CARL H. GRAESSER, OF BRIDGEPORT, CONNECTICUT, AS
SIGNORS TO MANNING, MAXWELL & MOORE, INC., OF NEW YORK, N. Y., A COR-
PORATION OF NEW JERSEY.

SAFETY VALVE.

Application filed August 11, 1921. Serial No. 491,614.

To all whom it may concern:

Be it known that we, PHILIP G. DARLING and CARL H. GRAESSER, citizens of the United States of America, and residents of Bridgeport, in the county of Fairfield and State of Connecticut, have invented new and useful Improvements in Safety Valves, of which the following is a specification.

This invention concerns safety valve devices and relates more particularly to a valve of that type commonly employed upon house heaters and the like, although in certain aspects the invention is of broader application.

Valves of the type referred to, when installed upon the ordinary house boiler, are commonly under the supervision of persons unskilled in mechanical matters and it is thus particularly desirable that such valves should be of simple construction and capable of withstanding rough usage. It is highly important, moreover, that such valves be maintained in operative condition and ready to blow at the proper pressure, and thus in many communities it is required by law that the safety valves of house heaters be so sealed after initial setting and inspection as to prevent readjustment of the spring tension by the user, while it is also required that some means be provided whereby the movable valve member or feather may be lifted manually from its seat at intervals to prevent it becoming attached to its seat by rust or scale.

The object of the present invention is to provide an improved valve of the above type having few and simple parts which will withstand rough usage without substantial damage; whose parts after once being properly adjusted cannot readily be reset without at least giving indication of such fact; and having a valve lifter lever which cannot be removed without dismantling the entire valve device.

In the accompanying drawings there is illustrated by way of example one form of valve device designed for carrying the above objects into effect; and in such drawings, to better illustrate the invention.

Fig. 1 is a vertical diametrical cross section to large scale of the complete valve device; Fig. 2 is a fragmentary plan view thereof; Fig. 3 is a side elevation of the valve casting or cap; and Fig. 4 is a side elevation of the valve lifter lever before assembly.

Fig. 3 is a side elevation of the valve casting or cap; and

Fig. 4 is a side elevation of the valve lifter lever before assembly.

The numeral 1 indicates a casting having external screw threads at 2 whereby it may be secured to the boiler shell or fitting. This casting is provided with a central bore 3 forming a steam passage, and at its upper end is furnished with a series of spaced, upwardly extending arms 4. These arms serve to support a ring 5 which may be integral with the arms if desired, and as herein shown. The ring 5 is externally screw threaded as shown at 6. The casting 1 provides a support for a bushing 7 which is secured therein in any desired manner. The upper edge of the bushing forms an annular valve seat as indicated at 8. Co-operating with such valve seat is a movable valve member comprising the disk 9 having the depending guide fins 10 which engage the interior surface of the sleeve 7 and which serve to maintain the disk in proper position relative to the seat surface of the bushing. Projecting upwardly from the center of the valve disk is a stem 11 which serves to support an abutment disk 12 of a diameter substantially larger than that of the stem. This abutment disk is preferably provided at its upper surface with an upstanding boss 13 which serves to center a coil compression spring 14 whose lower end bears against the upper surface of the abutment member 12.

For housing the movable valve member and its spring a casing or shell 15 is provided. This casing is preferably stamped from sheet metal and is of substantially conoidal form, having a smooth and unbroken outer surface. This casing or shell thus constitutes an inverted cup within which the spring and valve are housed. The lower portion or rim of the shell is substantially cylindrical and this portion is internally screw threaded as indicated at 16. The threads at 16 extend for a considerable distance longitudinally of the shell and are engageable with the threads 6 upon the ring 5. The upper or closed end of the casing, as indicated at 17, is of substantially spherical curvature, such end serving as an abutment for the upper end of the spring 14.

Due to the curvature of the inner surface of

the casing, the spring is automatically centered therein and maintained in axial alignment with the bore 3 without necessitating the employment of any additional parts 5 such as are commonly used in valves of ordinary construction. Moreover, by reason of the fact that the spring 14 bears directly against the inner surface of the housing, it is evident that by screwing the housing 10 down onto the ring 5, the tension of the spring 14 may be varied. Thus the employment of special adjusting nuts or similar devices is made unnecessary.

A narrow vertical slot 18 is formed in the 15 side wall of the casing 15, such slot serving for the reception of a valve lifter lever 19. This lever comprising an inner arm which bears at the point 20 against the under side of the abutment member 12 and a second and 20 longer arm 21 which extends in a generally vertical direction upon the outer side of the casing, and by means of which the lever may be manually actuated.

The valve lifter lever is preferably formed 25 by stamping the same from sheet metal and is provided with a tongue 23 which, when formed, lies substantially parallel to the edge 24 of the lever 19, as indicated in Fig. 4. After the casing 15 has been engaged with 30 the ring 5, the end of the lever 19 is inserted through the slot 18 and by means of a suitable tool the tongue 23 is caused to diverge from the surface 24 to an extent sufficient to prevent withdrawal of the lever through 35 the opening 18, the free extremity of the tongue 23 engaging the inner surface of the casing 15 at a point below the lower end of such opening and thus serving to retain the lever in operative position. After the casing 40 15 has been screwed down upon the ring 5 to provide the desired spring tension for the valve member, a hole 25 is drilled through the threaded portion of the casing, such hole also extending through the ring 5. This hole is preferably formed at a point 45 immediately above one of the legs 4, as for example leg 4^a and is then tapped for the reception of a screw 27. Upon insertion of the screw, the casing 15 is retained against 50 rotation relatively to the supporting casing 1 and thus the tension of the spring cannot be varied without removing such screw.

In order to prevent surreptitious removal 55 of the screw by unauthorized persons, the head of this screw may be provided with a transverse opening 28 through which a wire 29 is passed. This wire may be carried around the leg 4^a and its ends may then be secured together by means of any suitable 60 device, such as the lead seal 30. It is thus possible for the inspector who sets the valve spring at the proper tension to seal the valve device in such a manner as to show very clearly whether any attempt has been 65 made to tamper with the valve. The casing

15, providing a smooth and unobstructed exterior surface, is capable of withstanding extremely rough usage without permitting any damage to the enclosed parts, while the fact that the casing serves as the adjusting 70 and centering means for the spring serves to reduce the necessary parts to a minimum.

It is also to be noted that as the valve lifting lever fulcrums about the lower end 22 of the slot 18, it is unnecessary to provide a 75 pivot pin therefor, thus again reducing the number of parts and the operations necessary to the protection of a valve device of the desired character. By breaking the seal an inspector may remove the casing for 80 cleaning the valve parts, but in replacing the parts it is necessary to bring the opening 25 opposite the opening in the ring 5 in order to reinsert the screw 27 and thus it is possible to reset the valve to the same 85 tension as originally without necessitating the employment of a master gage in the resetting operation.

Having thus described the invention in a 90 preferred embodiment of the same, what I claim and desire to secure by Letters Patent of the United States is:

1. A valve device comprising a support, a valve, a spring normally holding the valve closed, and a unitary thin walled shell enclosing the spring and constituting an abutment for the upper end of the latter, said shell having a substantially cylindrical lower portion engageable with the support and conical side walls extending upwardly 100 from the cylindrical portion and merging into a spherically curved imperforate top.

2. A device comprising a support having a cylindrical externally threaded portion, a valve, a spring normally keeping the valve closed, and a shell enclosing the spring, said shell having a substantially cylindrical lower portion internally threaded for engagement with the support, and conical 105 walls extending upwardly from the cylindrical portion and merging into a smoothly rounded top.

3. A valve device comprising a support, a valve, a spring normally operative to keep the valve closed, and a casing enclosing the spring, said casing consisting of an integral sheet metal shell of substantially conical form having a rounded apex and a cylindrical rim portion, the rounded apex of the shell being smooth and imperforate 115 and provided with a spherically curved interior surface forming an abutment for one end of the spring.

4. A valve device comprising a support having an externally threaded portion, a valve, a spring for keeping it closed, and a shell of sheet material enclosing the spring and forming an adjustable abutment for one end of the spring whereby the tension of the spring may be regulated, said 125

- shell having an imperforate upper end smoothly rounded externally and provided with a curved inner surface against which the spring seats, and an internally threaded portion engaging the threaded part of the support, said internally threaded portion being of a length to permit substantial adjustment of the upper end of the casing toward and from the support.
5. A safety valve device comprising a spring controlled valve, a hollow shell forming a casing therefor, said shell having a vertical slot of fixed length in its wall, and a valve lifting lever fulcrumed upon the edge of the shell at the lower end of said slot and having a divergent tongue engageable with the interior surface of the shell whereby to prevent withdrawal of the lever from the opening.
10. 6. A safety valve device comprising a spring controlled valve, a hollow shell forming a casing therefor, said casing having a narrow slot of fixed length therethrough, and a valve lever fulcrumed upon the lower edge of said slot, said lever having an integral divergent tongue arranged within the casing and constructed and arranged to prevent withdrawal of the lever from the slot by engagement with the inner wall of the casing at a point beyond the end of the slot.
15. 7. A safety valve device comprising a hollow casing, a valve within said casing, and a valve lifting lever associated with said valve, said lever projecting outwardly through a narrow slot of fixed length in said casing and having an integral tongue within the casing diverging from the main portion of the lever to an extent preventing withdrawal of the lever from said slot.
20. 8. A valve device comprising an annular valve seat, a valve cooperable therewith, a spring for said valve, a casing for enclosing said valve and spring, said casing having a narrow vertical slot in its wall, a valve lifting lever of sheet material fulcrumed directly upon the edge of the casing proper at the lower end of the slot and having its inner end operatively connected to said valve and an integral tongue diverging from said inner end and having its free extremity constructed and arranged for engagement with the inner surface of the casing below the lower end of the slot.
25. 9. A valve lifting lever having a valve engaging portion and a retaining tongue projecting therefrom, said tongue being constructed and arranged to permit of its insertion together with the valve engaging portion of the lever through an opening in a valve casing, and then to be caused to diverge from said portion whereby to prevent withdrawal of said portion from the opening.
30. Signed by us at Bridgeport, Conn., this 8th day of August, 1921.
